MICROPHONE BOOM

Arthur George Wright, Los Angeles, Calif., assignor to Twentieth Century-Fox Film Corporation, Los Angeles, Calif., a corporation of New York

Application October 2, 1936, Serial No. 103,715

9 Claims. (Cl. 60—54.5)

This invention relates to extensible microphone booms and deals with a liquid operated boom.

The boom to be hereinafter described has been developed to meet the requirements of motion picture studio needs, but it will become evident as the description proceeds that it may find usefulness in other fields, such as broadcasting stations, or any other occasion where an extensible boom may be needed.

10 The principal object of this invention is to provide an extensible boom wherein the means for extending the boom comprises a liquid medium.

Another object is to reduce the noise common to the operation of the ordinary boom.

15 Still another object is to combine the counter-balancing weight necessary in booms of this nature with the means for actuating the liquid in extending the boom.

A further object is to provide an extensible 20 boom wherein the bulk of the external equipment common to the ordinary boom is either eliminated or concealed. In this respect, it is common knowledge that the ordinary boom comprises cables, pulleys, counter-balancing weights, 25 etc., as external equipment. In my invention, I eliminate the bulk of these and operate the extensible part of the boom by means of a non-compressible fluid, thus providing a positive action and avoiding lost motion due to cable slack.

30 A still further object is to provide an extensible boom characterized by workmanlike appearance, lightness, durability, and one wherein the cost of maintenance will be extremely low.

Other objects and advantages will appear as 35 the description proceeds in conjunction with the drawings in which:

Figure 1 is a side elevation of my boom complete, showing it partly extended with the supporting stand broken away.

40 Figure 2 is a longitudinal section slightly enlarged of the working parts of the boom.

Figure 3 is a cross section taken on line 3—3 of Figure 2.

45 Figure 4 is a cross section taken on line 4—4 of Figure 2.

Figure 5 is a cross section taken on line 5—5 of Figure 2.

50 Figure 6 is an enlarged section of the piston, showing the manner in which the piston is attached to the operating mechanism and the counter-balancing weight.

Figure 7 is an enlarged section of the piston on the extensible part of the boom, showing the manner in which the piston is attached to the 55 extensible rod.

Figure 8 shows a part of the rack with the connection to the piston gland.

Figure 9 is a longitudinal section slightly enlarged, showing the outer end of the boom and is a continuation of Figure 2.

5 Referring to the drawings and particularly to Figure 1, it will be seen that my boom consists, in general, of a stationary cylinder or barrel, generally designated A. Slidably mounted in the barrel A is a rod member B, and in the outer end 10 of this rod I mount another rod C, which is adapted to be telescoped within the rod B. The microphone D is attached to the end of the rod C by the conventional hanger E. At the rear end of the tubular member A and, as illustrated, 15 directly beneath this member, I mount another cylinder or tubular member F. The members A and F contain the liquid and the pistons to be later described. The members A and F are connected at the rear end by a suitable casting G, 20 which will be described in conjunction with the operation of the boom. The other end of the member F is held by a supporting box H. Extending forward of the box H is a smaller tubular member J, fixed at the forward end by a supporting spacer K. The box H is adapted to be supported on a stand L, which may take any form, and is arranged to swing in a vertical plane indicated by the dotted lines M and N.

In Figures 2 to 5 the construction and arrangement of parts is shown. Referring to Figure 2, which is an enlarged longitudinal section of the barrel arrangements with the pistons and moving parts, it will be observed that the barrel A passes through and is supported in the box H and contains an inner sleeve 11, which may be of thin, light material. The double sleeve arrangement provides a more rigid and a more durable construction. It is to be understood that the inner sleeve 11 extends the full length of the barrel A 40 and is spaced therefrom at one end by a casting 12. The casting 12 also carries the barrel A and the barrel F, which are mounted therein in any suitable manner. The other end of the sleeve 11 is spaced from the barrel A in any suitable manner, not shown. For this purpose a leather ring or screws extending through the barrel A may be used. Within the sleeve 11, the rod B is slidably mounted and is attached to a sliding support 13 and a piston 14 in a manner to allow a floating 50 action between the rod and the piston. This construction is best shown in Figure 7 and will be described later. The rod B is shown as square for purposes of rigidity and also to prevent rotation of the rod during extension. In Figure 1, 55

I have shown rollers 15 and 16 mounted on the barrel A. These rollers extend through the barrel and the inner sleeve 11 and are arranged to engage the upper and lower edges respectively of the square rod B. As the rod is extended, the rollers not only prevent turning of the rod, but also act as bearing points for the rod to prevent undue bending. On the outer end of the rod B, I mount a telescoping rod C, which is adapted to be extended by hand and on the outer end of the rod C I suspend a microphone D, mentioned before, by means of the conventional hanger E.

The foregoing description deals with the extensible part of the boom. The hydraulic means for extending the boom will now be described. As before stated, the barrel F is mounted directly beneath the barrel A, although it could be mounted above or to one side if more convenient, and is interconnected with the barrel A by means of a passage 17 in the casting G. A piston 18 is slidably mounted in the barrel F and is connected on one side to a sliding weight 19 and to a rack bar 20 on the other side. The barrels A and F are filled with a liquid between the pistons 14 and 18, thus forming a liquid link between the two pistons which works through the interconnecting passage 17. It is clear that the liquid connecting the two pistons being incompressible, and likewise non-expansible, will form a flexible connection between the two pistons that will operate to work the piston 14 in either direction. In other words, when the piston 18 applies pressure to the liquid, the piston 14 will normally move in response to the pressure and when the piston 18 moves in the opposite direction to withdraw the liquid the piston 14 will follow the withdrawal of the liquid, due to atmospheric pressure. It will be noted that the barrel F being considerably larger in diameter than the barrel A, the piston 14 will move farther than the movement of the piston 18 and that due to the arrangement of the two barrels the movement of the piston 14 is counter to the movement of the piston 18. The purpose of this is to move the weight opposite to the movement of the rod B, and thereby effect a counter-balancing action. For purposes of illustration and description, I have shown an auxiliary weight 19 attached to the piston, but it is obvious that the piston 18, being of a large diameter, may be made of sufficient length to act as a counterbalancing weight itself, if desired. An enlarged detail of this construction is shown in Figure 6. The rack bar 20 extends through the box H and is carried in the tubular member J. The means for working the rack bar backward and forward will be disclosed later in conjunction with Figure 5. The pistons 14 and 18 are connected by fluid, shown by the broken line portion in the barrels A and F. Referring now to Figures 6 and 7, a detailed description of the pistons 14 and 18 will be given. In these views, I have shown enlarged longitudinal sections of the pistons. The piston 18 comprises a hub 21 having an intermediate flange 22. Two cup leathers 23 and 24, placed back to back, are mounted on the hub and bear against opposite sides of the flange. The cup leathers are held in place by plates 25 and 26, respectively, which in turn are held by nuts 27 and 28, respectively, screw threadedly mounted on the ends of the hub 21. The hub is bored to receive a rod 29 that is pinned in the hub by a pin 30. In order to provide a floating connection between the rod 29 and the weight 19, I pass the rod completely through the weight before attaching it to the

weight. It will be noted that the rod does not touch the bushing 31, which is in the center of the weight. In Figure 2 it will be seen that the bushing 31 extends beyond the end of the weight and that the rod 29 is attached to this extended end by means of a pin 32, thus allowing the piston a floating movement with respect to the weight. The weight 19 is equipped with runners 33, which are circumferentially spaced and may be of any suitable material conducive to easy sliding and silent operation. Instead of making the weight separate from the piston, it may be incorporated as a part of the piston, if desirable. On the forward side of the piston, the hub 21 extends into a shaft 34, which is bifurcated at the end to receive the rack bar 20. A sliding connection is used between the shaft 34 and the rack bar 20, that is, there is a floating action between these two members. This is accomplished by making the bifurcation in the shaft larger than the tongue 35 on the rack. A pin 36 is used to connect the rack bar to the shaft and in order to obtain a full floating action, the pin is fixed to the tongue 35 and works in a transverse slot 37 in the shaft 34. A piston of this nature will have free action against the wall of the cylinder and will not be forced to accommodate itself to transverse movement either of the weight or the rack bar. In connecting the piston 14 to the rod B, I follow the same general idea, but not the same structure. This structure is shown in Figure 7. Here it can be seen that the piston itself consists of two cup leathers 38 and 39, mounted back to back against a flange 40 on a hub 41. The cup leathers are held in place by plates 42 and 43 respectively, which in turn are held on the hub by screw threaded members 44 and 45, mounted on the ends of the hub 41. The hub 41 is bored as at 46, and counterbored as at 47. A rod 48 extends through the bore 46 and is arranged to not touch any part of the hub 41. On the outer end of the rod I mount a screw 49 having a flat head. The head of the screw is adapted to fit in the counterbore 47 without touching the sides of the bore, but is arranged to engage the shoulder between the bore and the counterbore. With this arrangement, the piston 14 is loosely mounted on the rod 48. In conjunction with the cup leather arrangement, I provide means for carrying the end of the rod 50 B so that its weight will not come on the piston. For this purpose, I provide a hub 50 attached to the shaft 48 by a pin 51. The hub 50 carries a flange 52 against which there is fastened a fibrous member 53 adapted to engage the wall of the inner sleeve 11. The shaft 48 also extends through a block 54, which is adapted to fit into the end of the square rod B and both the block and the shaft are attached to the rod B by a pin 55. The structure just described will provide a full floating action of the piston 14 with respect to the rod B.

The actuating mechanism and the means for mounting the boom upon a support are shown in Figures 2 and 3. In Figure 3, I have shown a cross section of the box H. As before stated, the outer barrel A is mounted in the top of the box H and contains the inner sleeve 11 and the square rod B. Mounted on the barrel A are two upright standards with a bar 57 running between them for a handle for controlling the altitude of the boom or for swinging the boom on its support. The box H also supports one end of the barrel F, which is left open to the box. On the rear side of the box I form a hub 75

58, which is bored and equipped with a bushing 59. Inside the bushing, I provide a shaft 60 which is pressed into place and held stationary. Below the hub 58, and a little to one side thereof, I form another hub 61, into which a short shaft 62 is pressed and held stationary. The box extends around and down into a flange 63. On the front side of the box, I mount a door 64 and on the door I form another hub 65 which 10 may be provided with a bushing 66, if desirable. The door may be held in place by screws 67 or in any other suitable way. In the bushing 66 I mount another short shaft 68 and on the inner end of the shaft I fix a pinion gear 69. The 15 pinion gear is arranged to mesh with the rack bar 20 previously mentioned. On the outer end of the shaft 68 I attach a crank 70 for turning the gear 69. In order to provide good structure, the inner end of the shaft 68 is turned 20 down and extends into the shaft 60 as shown in dotted lines 68. From the foregoing description, it is evident that the door 64 may be removed and the pinion gear 69 withdrawn with the door, thus giving access into the box H and into the 25 end of the barrel F. Due to the fact that the rack bar 20 is made as light as possible, I recommend that a roller 71 be positioned beneath the bar to prevent bending. The hub 61 and the shaft 62 are for this purpose. In Figure 2, it can 30 be seen that the shaft 62 carries an arm 72 pivotally mounted thereon. The roller 71 is rotatably mounted on the end of this arm. Means is also provided for regulating the pressure of this roller against the rack bar 20, and as shown 35 comprises a screw 73 extending up through the bottom of the box H, with a set nut 74 for holding the screw once it is adjusted. From the foregoing it is obvious that the rotation of the crank 70 will move the piston 18 and the weight 19 backward or forward in the barrel F. The forward end of the rack bar in its travel is guided 40 in a groove 75 formed in a runner 76 of any suitable material in the member J, (see Figure 5). The box H may also be formed with an oil sump 77 having an outlet 78 therein. The whole assembly hereinbefore described is mounted on the support L. The mounting for this purpose is best shown in Figures 2 and 3. The support L may be any form of boom support, such as a 45 tripod or a standard of any description and carries on the upper end an upwardly extending arm 79 which may be properly reinforced as shown. On the upper end of the arm, I provide a hole adapted to receive a bolt 80, which is turned down and threaded in the shaft 60. Also on the upper end of the support, there is a slot 81 designed 50 to receive the flange 63 of the box H, when the box is supported by the bolt 80. It is to be understood that the bolt 80 turns in the arm 79 and that the flange 63 slides through the slot 81, thus permitting the boom to be swung in a vertical plane. My invention also provides means 55 for clamping the boom in any vertical position and as shown comprises a screw threaded bolt 82 mounted in the upper end of the support and adapted to engage and press the flange 63 in the slot 81. A short rod 83 may be used for turning the bolt 82.

In operation, the rod B is extended or retracted by turning the crank 70. As the crank is turned, the piston 18 together with the weight 19 is moved in the barrel F. This in turn, forces the liquid between the pistons 18 and 14 to move in response to the movement of the piston 18 and the piston 14 is correspondingly moved. As 60 mentioned before, the barrel A is of less diameter

than the barrel F and as a result the piston 14 is moved a greater distance than the piston 18. The weight 19 which moves with the piston 18 acts as counterbalancing weight for the extension of the rod B. By using a non-compressible 5 fluid, such as oil, between the pistons, the piston 14 may be made to follow the movement of the piston 18 with no lost motion, either for extension or retraction. The whole assembly is a compact, light, durable piece of equipment that 10 requires little or no maintenance and performs silently.

Although I have shown a detailed preferred form of my invention, I am aware that certain parts may be modified and refined without departing from the invention. I, therefore, intend this disclosure to cover all such alterations that come within the essence of the invention as expressed in the appended claims.

I claim:

1. In an extensible boom having a support intermediate its ends: a barrel; a rod slidably mounted in said barrel; a piston connected to said rod; a second barrel having an interconnecting passage to said first mentioned barrel; a piston in said second barrel; a weight attached to said piston; liquid connecting said pistons; and means for moving said piston and weight in said second barrel to move the piston and rod in said first mentioned barrel in an opposite direction. 20

2. In an extensible boom having a support intermediate its ends: a pair of interconnecting barrels; a piston in each of said barrels; a rod connected to one of said pistons and a weight connected to the other of said pistons; liquid connecting the pistons; and means for moving the piston and weight in one barrel to move the piston and rod in the other barrel in an opposite direction. 30

3. In an extensible boom having a support 40 intermediate its ends: a pair of barrels having an interconnecting passage at one end thereof; a piston in each of said barrels; a rod connected to one of said pistons and a weight connected to the other of said pistons; liquid connecting the 45 pistons; and means for moving the piston and weight in one of said barrels in one direction to move the piston and rod in the other barrel in the opposite direction.

4. An extensible boom comprising: a pair of 50 interconnecting barrels; means for supporting said boom intermediate its ends; a piston in each of said barrels; liquid connecting said pistons; a rod connected to one of said pistons; a weight and a rack bar connected to the other of said 55 pistons; a pinion gear mounted in said supporting means and adapted to mesh with said rack bar; and means for rotating said pinion gear to move said pistons, said barrels being arranged so that the movements of said pistons and their 60 associated parts are in opposite directions.

5. An extensible boom comprising: a first barrel and a second barrel having an interconnecting passage therebetween; a piston in said first barrel and a rod connected to said piston; a piston in 65 said second barrel; liquid connecting the two pistons; a weight and a rack bar attached to the piston in said second barrel; the piston in said second barrel being connected to the weight and rack bar to allow free transverse movement between the piston, the weight, and the rack bar; and means for moving said rack bar longitudinally to move said pistons, said barrels being arranged so that said pistons move in opposite 70 directions. 75

6. In an extensible boom having a support intermediate its ends: a pair of interconnected barrels; a piston in each of said barrels; liquid between said pistons; a rod attached to one of said pistons; a weight associated with the other piston; means for moving the piston and weight to move the piston and rod in an opposite direction.
7. In an extensible boom having a support intermediate its ends: a pair of interconnected barrels, one of said barrels being of larger diameter and shorter length than the other; a piston in each of said barrels; liquid connecting the pistons; a rod connected to the piston in the smaller barrel; a weight associated with the piston in the larger barrel; and means for moving the piston and the weight in the larger barrel to move the piston and the rod in the smaller barrel in an opposite direction.
8. In an extensible boom having a support intermediate its ends: a pair of interconnected barrels; a piston in each of said barrels; liquid connecting the pistons; a rod connected to one of said pistons and a weight associated with the other of said pistons; and means for moving said piston with its weight in one direction to counter-balance the movement of the piston and rod in an opposite direction.
9. In a counter-balanced extensible boom having a pivotal support: a pair of inter-connected barrels; a piston in each of said barrels; liquid connecting said pistons; a rod connected to one of said pistons and a weight associated with the other of said pistons; and means for moving said piston with its weight in one direction to maintain the balance of said boom and to move the piston and rod in an opposite direction.

ARTHUR GEORGE WRIGHT.
